INCLINED UNDERFEED RIVETING MACHINE
WITH MAGNETIC ANVILGifford B. Cranor, Jackson, Mich., assignor to
Tomkins-Johnson Company, Jackson, Mich., a
corporation of Michigan

Application January 10, 1950, Serial No. 137,830

2 Claims. (Cl. 218—2)

1

This invention relates to machines for upsetting upsettable members, such as clinch nuts, and particularly to machines which incorporate a reciprocable anvil onto which the upsettable members are delivered from a feed transfer mechanism and delivered to an upsetting die.

An example of the machine to which the present invention relates is somewhat fully disclosed in the prior U. S. Patent No. 2,163,440 granted June 20, 1939. The machine as disclosed in this prior patent is shown with a casing part containing the reciprocable anvil onto which the upsettable members are fed seriatim from a feed transfer mechanism while traveling in horizontal line formation. In the prior patent this casing part is shown as presenting a front wall which is perpendicular to the horizontal and the existence of which wall imposes a limitation upon the extent to which a workpiece, to which it is desired to affix upsettable members, can be moved forward into position between the opened-up anvil and die.

With the modern trend in automotive design, however, and the adoption of the prior art machine to the affixing of clinch nuts, for instance, to automotive fenders, for example, it happens that the existence of this perpendicular wall limits the use of the machine by preventing the fenders and other workpiece parts from being positioned sufficiently forward beneath the anvil, by appropriate manipulation of an overhanging portion of the workpiece positioned between the opened-up anvil and die, to permit the affixing of clinch nuts or the like over the required surface area of the workpieces.

An object of the present invention is to overcome the above mentioned defect of the prior art machine, and of riveting and like machines generally having a perpendicularly reciprocable anvil and perpendicular front casing wall, whereby workpieces can be positioned farther beneath the anvil to permit an overhanging portion of the workpiece between the anvil and the die to be moved farther across the opposed anvil and die surfaces than would be otherwise possible.

It is also an object of the invention to provide a riveting or like machine in which the upsettable members are magnetically attracted onto the anvil for feeding against the associated die and generally so to improve and modify the anvil and associated casing structure that not only is it possible to feed the upsettable members in a more positive and controlled manner than is possible with the prior art machines, but curved and bent shaped workpieces are capable of being

2

handled in the machine with the affixing of upsettable members thereto over a greater surface area than has been hitherto possible.

The above and other objects and advantages of the invention will become clear from a consideration of the following description with reference to the accompanying drawings, in which:

Fig. I is a fragmentary part vertical sectional view of the anvil and associated die of a riveting machine, showing the improved anvil construction with its magnetized supporting surface,

Fig. II is a detail view, in vertical section, showing the anvil ram with a clinch nut supported thereon, and the action of the ram in pushing back the line of clinch nuts in the feed transfer mechanism,

Fig. III is a transverse section on the line A—A of Fig. I,

Fig. IV is a transverse section on the line B—B of Fig. I,

Fig. V is a perspective view of the rear plate of the anvil, having the slot therein through which the clinch nuts are fed onto the anvil ram, and

Fig. VI is a perspective view of a clinch nut, such as can be handled by the present anvil construction, although the anvil construction can be adapted to handle other shapes and forms of upsettable members generally.

Referring to the drawings, 10 indicates the front casing portion of a riveting machine in which the anvil structure is mounted and which casing portion, to conform with present day requirements, is formed with a rearwardly inclined front face 12.

For a complete understanding of the general construction and operation of the riveting machine reference may be made to U. S. Patent No. 2,163,440, patented June 20, 1939. It is sufficient to point out herein that the rearward inclination of the front casing face 12 gives rise to the necessity of employing a correspondingly inclined anvil structure if the anvil cam 14 is to deliver the upsettable members beneath the die, indicated generally at 16.

Such an inclined mounting of the anvil structure is shown in Figs. I and II.

The anvil structure is composed of the outer body 18, which is of channel section, as appears clear in Figs. III and IV, and in which outer body there is mounted the anvil ram 14, this ram being reciprocable within the body 18 under the control of a toggle mechanism comprising the links 20, 22 and the toggle actuator rod 24, pivotally connected with the links at 26.

The toggle link 22 is pivotally connected at its lower end about the fixed pivot 28 whereas the toggle link 20 is pivotally connected at its upper end about a pivot 30 upon a block 32, which block is slidably within the casing portion 10 and is rigidly connected with the lower end of the anvil ram 14 by the stud 34.

The anvil body 18 is adapted to be clamped into fixed position upon the front of the casing 10, as by the clamp housing 36, which, in effect, forms part of the machine casing and includes the front inclined wall surface 12.

The anvil channel section body 18 is employed in conjunction with a separate plate 38, which closes the open side of the channel and has a slot 40 therein through which the clinch nuts are fed onto the ram, as will be described later. The plate 38 also has screw holes 42, which receive screws 44 for attaching a plate 46 to the plate 38, the plate 46 having a bent sprung lip portion 48, the upper edge portion of which is disposed to be slightly in the path of the clinch nut supported upon the anvil ram, as and for the purpose to be described later.

The plate 38 is provided with side recesses 50 in which pins 52 on the fixed machine casing sides 10 engage to prevent undue upward movement of the plate, bearing in mind that the plate is held clamped against the edges of the casing sides 10 by the pressure applied by the clamp housing 36 and that the plate 38 is subjected to the friction sliding motion of the anvil ram 14. These recesses 50 and pins 52, however, constitute merely a safety feature in case the plate 38 should be moved as stated and which is not likely to happen in the general use of the machine.

Dealing further with the anvil construction, an important feature of the present invention resides in the provision of the anvil ram 14 with a permanent magnet insert 54 in the form of a plug secured in a bore 56 in the upper end of the anvil and machine finished at its upper end to provide a horizontal surface 58 flush with the abounding horizontal surface portion 60 of the anvil. This surface portion 60 is of rectangular outline, as seen in Figs. III and IV, and along its side remote from the clinch nut entry slot 40 is provided with an upstanding shallow flange 62 of a depth corresponding substantially to the depth of the flange portion 64 of the clinch nut 66, (Fig. VI).

The clinch nuts are fed to the anvil in horizontal line formation along a horizontal magazine 68, to which the clinch nuts are delivered from an overhead hopper and associated chute (not shown) and in such manner that the line of clinch nuts is constantly urged forward.

In the operation of the anvil, when the anvil ram 14 is in the lowered position as shown in dotted lines in Fig. I, the anvil surface, constituted by the magnet surface 58 and the abounding anvil surface 60, is positioned in line with the line of clinch nuts in the horizontal magazine 68, as well as opposite the slot 40. A clinch nut 66 is therefore pushed through the slot onto the anvil surface, being attracted thereto by the magnet 54 and being properly located upon the anvil by abutting against the upstanding flange 62.

The anvil ram is shown with a tapered front surface 69 which, at the commencement of the upward movement of the ram, contacts with the

clinch nut immediately behind the clinch nut on the anvil and cams the line of clinch nuts back along the magazine, as seen in Fig. II, thereby freeing the anvil ram to be lifted to position the clinch nut opposite the die 16 for operation thereon to clinch the lifted nut onto the metal sheet 70, seen in Fig. I.

Upon being lifted to the top of the fixed anvil structure 18 the side of the clinch nut remote from the abutment flange 62 is lightly engaged by the free edge portion of the sprung portion 48 of the plate 46 and by the resulting spring action serves to retain the clinch nut properly located upon the anvil for the desired clinching operation, performed by the die head 72.

The invention provides an exceedingly useful and efficient anvil construction, with which upsettable members can be fed for upsetting in a positive and reliable manner, while enabling an inclined arrangement of the anvil and the associated front casing surface to be employed with the attendant advantage that the machine is able to handle a greater variety of differently shaped articles than is possible with the existing machine constructions. Having thus described my invention in detail and in one particular form, by way of example, but without limitation to the precise details therein involved, what I claim as novel and wish to secure by Letters Patent is as follows:

1. In a machine for upsetting rivets and the like, fixed frame structure defining an upper horizontal surface and a front wall downwardly and rearwardly inclined from said surface, said surface supporting a horizontal rivet feed magazine, said frame structure having an elongated guide slot vertically inclined in corresponding relation to said inclined front wall, a rivet feeding ram, means mounting said ram for vertical reciprocation in said slot to feed the rivet against an upsetting die, said ram having a horizontal top surface with an upstanding abutment at the side thereof remote from a side opening in an upstanding wall portion of said frame structure through which said side opening a rivet is capable of being fed from said magazine onto said ram surface, a recess in said ram surface, and a permanent magnet mounted in said recess with its upper end flush with said ram surface, said abutment serving fully to position a rivet upon said ram surface.

2. A rivet upsetting machine as claimed in claim 1, said ram presenting a bevelled surface on the side thereof adjacent said side opening, said bevelled surface being inclined downwardly and rearwardly from said top ram surface, whereby the corresponding side of said surface is spaced from said side opening.
